(74) Attorney, Agent, or Firm — Andrus Intellectual Property Law, LLP

CLAIM

The ornamental design for a dipstick, as shown and described.

DESCRIPTION

FIG. 1 is a perspective view of the dipstick showing my new design.

FIG. 2 is a perspective view of an enlarged detail of FIG. 1. FIG. 3 is a top view of the enlarged detail view thereof, which is also representative of the opposite, bottom view; and,

FIG. 4 is a side view of the enlarged detail thereof, which is also representative of the opposite, side view.

(Continued)

The broken lines in the drawings illustrate portions of the dipstick that form no part of the claimed design. The dash-dot lines illustrate a break in the design and form no part of the claimed designed. The dipstick is shown with a break in the middle of the design. The portions of the design not shown form no part of the claimed design.

1 Claim, 3 Drawing Sheets
